By *Henry W. J. 3* atty.

UNITED STATES PATENT OFFICE.

CARL AXEL WILHELM HULTMAN, OF STOCKHOLM, SWEDEN.

AUTOMATIC SELECTOR-SWITCH.

1,186,908.

Specification of Letters Patent. Patented June 13, 1916.

Application filed July 9, 1914. Serial No. 849,933.

To all whom it may concern:

Be it known that I, CARL AXEL WILHELM HULTMAN, a citizen of the Kingdom of Sweden, residing at Stockholm, Sweden, 5 have invented new and useful Improvements in Automatic Selector-Switches, of which the following is a specification.

My invention relates to automatic selector switches of the kind used in telephone exchanges and in which rotatable and longitudinally movable means are provided to bring about the connections desired.

The object of this invention is to provide a simple and compactly arranged switch of the kind in which the lines end in fixed terminals and in which no movable terminals are used, the rotatable and longitudinally movable means being electrically independent of the circuit of the fixed terminals 20 and only adapted to bring said fixed terminals into contact with each other.

The invention will be more particularly described and further features thereof pointed out by reference to the accompanying drawing which by way of example illustrates, partially in vertical section, a selector embodying my invention.

Referring to the drawing, 1 is the shaft of the selector switch said shaft being electrically independent of the circuits of the selector. The shaft 1 can be rotated by any well-known driving means, as for instance by means of a driving shaft 8 rotating intermittently or continuously and journaled 35 in a frame 24, and bevel wheels 9 and 10, the wheel 9 being attached to the shaft 1 and the wheel 10 to the driving shaft 8, or I may use a step magnet for such purpose. The shaft supports two systems of arms 2, 40 2¹ by means of which the terminals to be actuated by the selector are acted upon. Said terminals consist of springs 3, 4, 3¹, 4¹ arranged in two concentric groups at each system of arms. The springs 3, 4 effect for 45 instance the connection of a number of speaking wires with a connecting wire in the telephone office, whereas by means of the springs 3¹, 4¹ the testing wires belonging to said speaking wires may be connected with 50 a corresponding wire in the telephone office.

The shaft 1 is movable in longitudinal direction. Normally the shaft is in its upper position with the gears 9, 10, out of mesh, but when it is to be rotated it is low-

ered to a certain extent so as to bring the 55 gears into mesh. Said movement in longitudinal direction may be effected by means of a solenoid or an electromagnetic device or in any other manner. Thereby the system of arms 2 will be moved away from the 60 inwardly bent ends of the contact springs 3 so that the arms cannot touch said springs whereas the arms 2¹ are always able to close the contacts 3¹ when the shaft is rotated. When the desired testing wire has 65 been found and the selector, on account thereof, has been stopped, the shaft 1 will, by means of a coiled spring 7, be moved axially to its original position so that the 70 contacts of the speaking wires corresponding to the testing wire found are closed.

Having now described my invention what I claim as new and desire to secure by Letters Patent is:

1. In a selector switch, the combination 75 with a rotatable and longitudinally movable shaft and systems of arms mounted thereon, of two concentric rows of fixed terminals for each arm system, the terminals of the inner row being adapted to be operated by 80 the corresponding arm system, whereas the terminals of the outer row are adapted to be engaged by the corresponding terminal of the inner row when the latter are acted upon by the arms, said arms being electrically independent of the circuits of the 85 terminals.

2. In a selector switch, the combination 90 with a rotatable and longitudinally movable shaft and two systems of arms mounted thereon and electrically independent of the circuits of the selector, of two concentric rows of fixed terminals for each arm system, the terminals of the inner row corresponding 95 to one arm system being adapted to be acted upon by said arm system during the rotation of the shaft whereas the terminals of the inner row corresponding to the other arm system are adapted to be acted upon by this arm system after the shaft has completed its rotation and moves longitudinally.

In testimony that I claim the foregoing as my invention, I have signed my name in presence of two subscribing witnesses.

CARL AXEL WILHELM HULTMAN.
